(57) **CLAIM**

The ornamental design for a small joint surgical access cannula as shown and described.

DESCRIPTION

FIG. 1 is a front perspective view of a small joint surgical access cannula.

FIG. 2 is a rear perspective view thereof.

FIG. 3 is a top plan view thereof.

FIG. 4 is a bottom plan view thereof; and,

FIG. 5 is a right side view thereof, the other side view being a mirror image of FIG. 5.

The broken lines in the drawings depict portions of the small joint surgical access cannula and form no part of the claimed design.
